William W. Bryman, of West Meriden, Conn.
Letters Patent No. 1617, dated Aug. 5, 1862,

The schedule referred to in these Letters Patent and making part of the same.

To all whom it may concern:

Des. 1617

Be it known that I, William W. Bryman, of West Meriden County of New Haven, and State of Connecticut, have invented or produced a new and original design for Fruit Can; and I do hereby declare that the following is a full and exact description of the same.

In the accompanying photographic views are shown my improved design for fruit can.

A. is the can. B. is the neck or upper end of the can, having a groove C, ring D, and vent depression E, configurated thereon substantially as described to produce a plain and much desired design for fruit can for preserving fruit &c.

What I claim therefore and desire to secure by Letters Patent, is the design for a fruit can, substantially as shown and described.
